LOOSE LEAF BINDER

Edward C. Rankin, Oak Park, Ill., assignor to Brock and Rankin, Inc., Chicago, Ill., a corporation of Illinois

Application April 12, 1956, Serial No. 577,852

1. Claim. (Cl. 129—17)

The disclosure relates to improvements in loose-leaf binders, more particularly the divided-ring variety operating on the centrally hinged wing principle.

The invention has as its chief objective the provision of a loose-leaf binder of the class described characterized by versatility, simplification, and especially reduced manufacturing costs while retaining capabilities of much more costly and complex binders of this general class.

More particular features relate to the provision of a simple flat-backed metal cradle for mounting the mechanism as a subassembly ready for attachment to the flat casing backbone; to the provision of a simple, very compact automatic latch means for controlling partial- and full-opening movements of the wings; to the provision of a simple over-center closing leverage, together with a rigidifying guide means for the middle-break hinge means.

Still further aspects of novelty and utility will appear as the following description proceeds in view of the annexed drawings, in which:

Fig. 1 is a perspective of the binder in loaded condition viewed from the lower or latch end;

Fig. 2 is an enlarged elevational view looking into the empty binder at the binding mechanism;

Fig. 3 is a fragmentary end view looking at the latch end of the binding mechanism in the partially open, reading position;

Fig. 4 is a plan view of the binding mechanism looking down upon the same in its condition of Fig. 3;

Fig. 5 is a view similar to that of Fig. 4 but with the binder rings in full-open or loading position;

Fig. 6 is a cross-section taken along lines 6—6 of Fig. 2;

Fig. 7 is a cross-sectional detail taken along lines 7—7 of Fig. 4 with the binder in the partially-open or reading condition;

Fig. 8 is a cross-section taken along lines 8—8 of Fig. 5 showing the rings in full-open condition;

Fig. 9 is a longitudinal section taken along lines 9—9 of Fig. 2.

As viewed in Fig. 1, the binder consists of a pair of hard covers 12, 13 hingedly joined to a hard, flat backbone 14 to the inside face of which is attached by blind rivets 15 (Fig. 2) the metal cradle of the binder mechanism generally indicated at 16.

Referring now to Fig. 3, the bound loose-leaf material, such as the leaves L (Fig. 1) or L₁, L₂ (shown divided in Fig. 3) will be strung on arcuate posts, prongs or stringers 18, 19 respectively attached to left and right wings 20 and 21, which are V-shaped in cross-section (as in Fig. 7) and have mutually interfitting hinge bores formed along their confronting longitudinal margins at 22 and joined by a long hinge pin 23, which is seen in dotted lines in Fig. 2.

The movements of the wings 20, 21 are especially guided and stabilized by means attached to or forming part of the cradle, including a pair of upstanding guide

flanges 24, 25 (Fig. 9) secured by the same rivets 15 which attach the cradle 16 to the backbone 14.

Each said guide flange has a long vertical slot 24X or 25X (Figs. 3 and 8) which straddles the hinge rod 23, as seen especially in Fig. 9, so that said rod is confined to a fixed vertical track in the opening and closing movements of the wings.

A further guide means for the wings comprises (as seen in Fig. 4) a long rod 30 or 31 attached respectively

10 to the wings 20 or 21 by a clip and speed-nut means 30A or 31A, each said rod having both of its ends provided with a crank-shaped offset 30X or 31X projecting into a corresponding horizontal runway slot 32 or 33 (Fig. 3) formed in the opposite, upstanding end walls 16A of the cradle.

At the lower or foot end of the cradle (Fig. 1) is a small latch plate 35 having an offset bottom edge 35A (Fig. 9) riveted as at 36 to a pair of flat springs 37 anchored by rivets 15 on spacers 13' beneath the cradle in such manner that the latch plate 35 normally stands upright and nearly flush against the end of the cradle such that one of each of the offset guide rod portions 30X and 31X will respectively flank the latch plate 35 at one of the vertical side edges of the latter; whereby the said rod offsets are prevented from moving inwardly in the slots, as they must do if the two wings are to be permitted to open.

However, as depicted in Fig. 3, the guide slots 32, 33 for said offset rod ends are long enough to permit limited opening movement of the wings from the fully closed condition shown in Fig. 6 to the first or partially open reading position shown in Fig. 3, wherein said rod offsets abut the edges of the latch plate 35, which prevents further opening movement of the wings unless the latch plate 35 is sprung outwardly to permit the full-open condition shown in Fig. 5 wherein the ends of the rod offsets are pressed against by the latch plate, with the latter thereby held in open condition until such time as the wings are closed or converged. When the latter movement has progressed far enough the latch plate 35 will spring back to blocking position (Fig. 4).

When the full-open or loading condition of the wings prevails, as in Fig. 5, the pivotal axis thereof along hinge rod 23 shifts upwardly, as in Fig. 8, to the top of the slots in the vertical guide posts 24, 25, and the closing force applied to the wings is then applied at a level somewhat above the elevated level of the hinge rod 23 for which purpose closing levers 40, 41 (Figs. 8 and 9) are attached to the ends of the wings opposite from the foot or latch end, said levers being attached to the wings preferably by rivets through angled foot portions on each lever, as indicated at 42 in Fig. 2.

Smaller angles 44 (Fig. 2) are similarly riveted into position on the foot ends of the wings near the latch, the offset crank ends 30X, 31X on the wing guide rods projecting through holes cut in said levers and angles, as at 45 in Fig. 2. By this means the guide rods 30, 31 are rigidly coupled with their respective wings 20, 21.

60 In the operation of the new binder, mere dividing of the pages and opening on a flat surface (as in Fig. 3) will cause the wings 20, 21 to rock open to the reading condition with the leaves L₁, L₂ more or less flat.

In this latter condition the ends 30X and 31X of the guide rods on these wings bear against opposite vertical edges of the latch plate, as in Fig. 3, to prevent the wings from opening farther; and to prevent the leaves from disengaging the binder rings 18, 19 the latter have some relative overlap, as at 18X (Fig. 3).

70 For removal or insertion of leaves, the latch plate 35 (Fig. 5) is pulled out and the wings will drop to fully

open position, as in Fig. 8, with the rings 18, 19 spread open.

To close the binding mechanism from the condition of Fig. 8, the two upstanding levers 40, 41 are squeezed between the thumb and forefinger, and the existing leverages then cause the wings, even when heavily burdened with pages, to swing up easily and positively, owing to the action of the several guide rod and hinge rod means in their respective guiding slots.

It should be noted that the pivotal action of the wings 20, 21 are complex and take place about several axes simultaneously, i.e. a central common axis through the hinge rod 23, which also shifts up and down in a vertical plane; and about the axes through their respective offset projections 30X, 31X on the guide rods, the latter also shifting simultaneously in a horizontal plane.

But, unlike other binding mechanism of this general class, such movements are effected by a very simple, compact, relatively inexpensive mechanism working within the confines of a lesser volume than any known prior type of binder utilizing the middle break principle.

Any standard flat-back casings or covers may be used with the new mechanism whether the attaching rivets are blind or not, and the covers may be double or single hinged.

I claim:

In a loose-leaf binder of the known class having a pair of long, prong-carrying wing members joined to a long common central hinge axis, together with mounting means

therefor and guided stud means at an end of each wing spaced from the hinge axis and respectively working in guide slot means to guide the wings in opening and closing rocking hinge movement such that the hinge axis moves up and down in opening and closing action of the prongs, improvements comprising, namely: a lock for these wings consisting in a transversely directed plate member having guide slot means directed transversely of said axis and positioned opposite one end of the pair of wings, and stud means on each wing end projecting into and beyond said slot means for back and forth guided movement to cause rocking of the appertaining wings as the hinge axis moves up or down as aforesaid; and a latch member and means mounting the same adjacent said plate member for movement into blocking position in between said projecting stud means to prevent rocking movement of the wings as aforesaid, or permit such movement when the latch member is withdrawn from said blocking position.
